UNITED STATES PATENT OFFICE.

WOOLF SCHAFFER, OF LONDON, ENGLAND.

HAIR FRAME, PAD, OR ROLL FOR LADIES' USE.

No. 914,191.

Specification of Letters Patent.

Patented March 2, 1909.

Application filed July 20, 1908. Serial No. 444,381.

To all whom it may concern:

Be it known that I, WOOLF SCHAFFER, a subject of the King of Great Britain, residing at London, England, have invented certain new and useful Improvements in Hair Frames, Pads, or Rolls for Ladies' Use, of which the following is a specification.

My invention relates to an improved construction of hair frame, pad or roll for ladies' use, whereby such article is made cheaply, light in weight, flexible in character, and capable of being manipulated without being altered or losing its shape or contour.

My invention will be clearly understood from the following description aided by the accompanying drawings, which show several examples of my invention but it must be understood that frames, pads or rolls of other shapes can be made.

Figure 1. is a side elevation of a hair pad or roll (broken) one part showing the interior tube partly in section. Fig. 2. is a view of a hair frame. Fig. 3. is a cross section of Figs. 1 or 2. Fig. 4. is a cross section of a **D** shaped hair pad, frame or roll. Fig. 5. is a cross section of a triangle shaped hair pad, frame or roll.

For the purpose of my invention, I make the foundation or center A of hollow or tubular formation from open or close meshed fabric or paper or other wireless material, plaited or creased, so as to form a bellows like tube. Around this tube or core A I wind, wrap or otherwise arrange hair, silk, or other fibrous material B resembling hair, and of a color to suit ladies' hair, said fibrous

material B being inclosed and held on the tube A by a tubular net C of the same color, the net C being practically invisible as a net. The ends of the tubular net may be secured by any means. The tube or core A may be slightly stiffened if the material is of an easily collapsible nature, and will not by itself hold itself in tube formation, and by plaiting it in bellows form as at Fig. 1, it can be bent in any position to suit the style of hair dressing without fear of its collapsing or stretching and breaking the net or disarranging the fibrous material.

I prefer to construct the core from a strip of fabric, then plait it across its length, and then make it into tubular form on a rod or otherwise, and stick or sew the edges together to form the tube. The tube or core can be made of any shape and length, either one long tube as at Fig. 1, or crescent shaped as at Fig. 2 or otherwise, and in cross section it may also be of any shape.

What I do claim and desire to secure by Letters Patent is:

A hair frame, pad or roll for ladies' use, consisting of a plaited bellows like tube surrounded by fibrous material and a tubular net substantially as set forth.

In testimony whereof I have hereunto set my hand in presence of two subscribing witnesses.

WOOLF SCHAFFER.
